UNITED STATES PATENT OFFICE.

GERALD F. KELLY, OF NEW YORK, N. Y.

PAPER DISPLAY BOX.

1,414,363.

Specification of Letters Patent.

Patented May 2, 1922.

Application filed May 29, 1920. Serial No. 385,190.

To all whom it may concern:

Be it known that I, GERALD F. KELLY, a citizen of the United States, and a resident of New York city, in the county of Bronx 5 and State of New York, have invented certain new and useful Improvements in Paper Display Boxes, of which the following is a specification.

The invention pertains more particularly 10 to a novel construction of box adapted to hold merchandise and to be utilized as a display box on counters, show cases and the like, the box then being in an open condition exposing the merchandise and the lid 15 for the box being turned to an inclined position and exposing on its then front face an advertisement or other display matter.

The box of my invention is formed from 20 a single blank of paste-board or the like folded to form the box and its lid, the parts of the blank being so constructed that the box when formed therefrom is of rigid durable character and has its parts interlocked so as to maintain the integrity of the box, 25 without the use of rivets, glue or the like.

One purpose of my invention is to produce a display box of comparatively inexpensive character and of large capacity and requiring a limited amount of supporting 30 surface on a counter, glass case or the like.

The invention will be fully understood from the detailed description hereinafter presented, reference being had to the accompanying drawings, in which:

35 Fig. 1 is a plan view of the blank from which the box of my invention may be produced, the dotted lines indicating the fold lines of the blank;

40 Fig. 2 is a perspective view showing the blank in a partly folded state or in the process of being folded to create the box;

Fig. 3 is a vertical section through a portion of the completed box, the section having been taken on the dotted line 3—3 of Fig. 7;

45 Fig. 4 is a perspective view of the complete box with the lid thereof open and the front flap thereon as not having been detached;

Fig. 5 is a perspective view of the completed box shown in its closed condition;

50 Fig. 6 is a perspective view of the box shown in its open display position exposing the merchandise therein and as having had the front flap detached from the open lid of the box, said flap being shown as connected 55 with the lid in Fig. 4;

Fig. 7 is a horizontal section on a larger

scale through the body of the box, the section being on the dotted line 7—7 of Fig. 8, and

Fig. 8 is a vertical section through the 60 same, taken on the dotted line 8—8 of Fig. 7.

In the drawings, referring to Fig. 1, 10 designates the blank from which the box of my invention may be produced, said blank being of the special construction devised by 65 me from which to make the box. The blank 10 has a substantially central panel 11, which finally constitutes the back of the box, and from one side edge of the panel 11 extends a panel 12, while from the opposite side edge 70 thereof extends a panel 13 which is of about the same dimensions as the panel 12. From opposite end edges of the panel 11 extend corresponding panels 14, 15, respectively, which are elongated and subdivided by fold lines 75 16, 17, 18, respectively, into auxiliary panels 19, 20, 21, respectively. The panels 14, 15 join the panel 11 by weakened or fold lines 22, 23, respectively, and the panels 12, 13 join the panel 11 by weakened or fold lines 80 24, 25, respectively. The panel 12 which finally constitutes a lid for the box has joined to it by a weakened or fold line 26 a front flap panel 27. The panel 13 has joined to it at its opposite side edges by fold lines 85 28, 29, respectively, corresponding panels 30, 31 which finally constitute inner vertical side members for the box and extend upwardly from the side edges of the panel 13 which will constitute the bottom of the box. 90

At the opposite end portions of the front of the bottom panel 13 are two extensions 32, 33 which are separated by a broad space 34 and joined to the panel 13 along weakened or fold lines 34, 35.

95 The blank having been cut to the outline shown in Fig. 1 and scored along the fold or weakened lines hereinbefore enumerated, may be folded to produce the complete box shown in Figs. 4 and 5. In the formation of 100 the box from the blank shown in Fig. 1, the folding of the panels to create the box may be performed by several successions of stages, but preferably I will fold the side members 30, 31 upwardly on the fold lines 105 28, 29 and then turn the panel section 11 upwardly against the rear edges of the side members 30, 31 to form the back of the box. I then turn the extensions 32, 33 upwardly and they will then appear at the 110 front corners of the bottom panel 13 and at the front edges of the side panels 30, 31.

The wings or sections 14, 15 may then be folded forwardly on the fold lines 22, 23 and the outer end portions of said wings or sections 14, 15 may be folded on the lines 5 16, 17, 18, the first fold taking place on the line 16 and then on the lines 17, 18 so that the panel 19 may stand at the front of the box, the panel 20 lie against the reverse face of the panel 19 and the panel 21 lie against 10 the side member represented by the panel 14 or 15, whereby a front corner construction is produced from each of the sections 14, 15 which is of double thickness, as shown at the right hand side of Fig. 2. The outer end 15 of the sections 14, 15 are thus constructed and folded, and said sections are folded on the lines 22, 23 to form the outer sides of the box and lie against the inner side members, 30, 31 thereof. The outer side members 20 14, 15 of the box are locked in their final position by the entry of the extensions 32, 33 of the bottom 13 between the panels 19, 20 formed at the ends of said side members 14, 15, and the entry of said extensions 25 between said panels may take place by the folding of the sections 14, 15 on the lines 17, 18 around the extensions 32, 33, respectively, the first fold on the line 16 taking place at the front edge of the inner side member 30 30 or 31, as the case may be, and the fold on the line 17 then taking place at the inner edge of the extension or projection 32 or 33, as the case may be, and the final folding on the line 18 then taking place so as to carry 35 the panel 20 against the inner or reverse face of said extension or projection 19 and the panel 21 against the inner side of a side member of the box. The panels 19, 20, 21 at the front corners of the box render said 40 corners strong and capable of withstanding severe strains, and said panels cooperate with the extensions or projections 32, 33 in completing the front of the box, said extensions or projections when held between the 45 panels 19, 20 serving as keys to lock the box in its finished formation. The side members 30, 31 cooperate with the side members 14, 15 to provide strong sides for the finished box. The lid panel 12 may finally be folded 50 over on the body of the box, along the fold line 24, and the flap 27 may be folded downwardly on the fold line 26 and tucked in between the merchandise that may be within the box and the inner faces of the panels 20, 55 or to the position shown in Fig. 5 which shows the box in the condition it will occupy during transportation or at any other time in which it may not be desired to display the merchandise held by the box. It is to be 60 noticed that there is a wide space at the front of the box between the facing edges of the panels 19, and this space may be closed by the flap 27 when the box is not in use as a display box, and said space is intended to be 65 left entirely open when the box is employed

on a counter for the display of the merchandise that may be therein. When the box is to be employed as a display box, the flap 27 will be drawn upwardly from behind the front corner panels of the body of the 70 box and detached from the lid panel 12 and thereupon the panel 12 will be turned to the inclined position in which the same is illustrated in Fig. 6 so that said panel may display to the customer any advertisement, 75 trade mark or the like that may be displayed on the face thereof, this face being the lower face of the lid panel when the box is closed and the front face thereof when said lid panel is turned to its inclined position. 80

I illustrate the box in Fig. 6 as containing two horizontal rows of packages of candies, chiclets or the like arranged on edge, and my box is of such formation that I may conveniently display the fronts of said rows 85 of merchandise so that the names thereon may be seen by a customer. The packages of merchandise may readily be lifted from the box, since the front thereof is open and the lid raised. The box has a considerable 90 capacity and at the same time occupies a minimum amount of space on a counter or show case. The box is in one piece of material whose parts are so shaped and arranged that the box itself may be conveniently produced therefrom without the aid of rivets, glue or the like. The box is also of durable character and capable of resisting the usual handling which boxes of this nature receive when in use. In addition the box is comparatively inexpensive and admirably serves 95 as a counter display box. 100

What I claim as my invention and desire to secure by Letters Patent, is—

1. A merchandise display box comprising 105 a bottom, a back, sides, and a front whose corner portions are formed by extensions of said sides folded toward each other and then reversely to form two plies, said front between said corner portions being open and said bottom at its front corner edges having upwardly extending members located between the plies of said corner portions. 110

2. A merchandise display box comprising 115 a bottom, a back, a hinged lid extending forwardly from the upper edge of said back and having a detachable flap to close the front of the box, sides and a front whose corner portions are formed by extensions of said sides folded toward each other and then reversely to form two plies, said front between said corner portions being open and said bottom at its front corner edges having upwardly extending members located between the plies of said corner portions. 120

3. A merchandise display box comprising 125 a bottom, a back, inner side members extending upwardly from opposite edges of said bottom, outer side members extending forwardly from opposite edges of said back, 130

- and a front whose corner portions are formed by extensions of said outer side members folded toward each other and then reversely to form two plies, said front between said corner portions being open and said bottom at its front corner edges having upwardly extending members located between the plies of said corner portions. 5
4. A merchandise display box comprising a bottom, a back, a hinged lid extending forwardly from the upper edge of said back and having a detachable front flap to close the front of the box, inner side members extending upwardly from opposite edges of 10 said bottom, outer side members extending forwardly from opposite edges of said back, and a front whose corner portions are formed by extensions of said outer side members folded toward each other and then 15 reversely to form two plies, said front between said corner portions being open and said bottom at its front corner edges having upwardly extending members located between the plies of said corner portions. 20
5. A merchandise display box comprising a bottom, a back, inner side members extending upwardly from opposite edges of said bottom, outer side members extending forwardly from opposite edges of said back, 25 and a front whose corner portions are formed
- by extensions of said outer side members folded toward each other and then reversely, forming two front plies, and then rearwardly along the sides of the box, said front between said corner portions being open and 30 said bottom at its front corner edges having upwardly extending members located between the front plies of said corner portions. 35
6. A merchandise display box of the character described having, in one integral blank, a bottom, a back, sides, front portions extending toward each other from the front vertical edges of the sides of the box and which portions are spaced apart to leave the front of the box open between said front 40 portions for exposing thereat such merchandise as may be placed in the box, and a lid hinged to the upper edge of said back and having a front flap hinged thereto adapted to extend downwardly against said front inwardly-extending corner portions of the box and close the front opening formed between said portions, and said lid being adapted to be inclined upwardly and rearwardly on the upper edge of said back to display such data 45 as may be thereon. 50

Signed at New York city, in the county of New York and State of New York, this 27th day of May, A. D. 1920.

GERALD F. KELLY.
